UNITED STATES PATENT OFFICE

FRANK ZWINK, OF LOUP CITY, NEBRASKA

ENSILAGE ELEVATOR FOR PIT SILOS

Application filed January 25, 1929. Serial No. 335,131.

This invention aims to provide a simple means whereby a person can lower himself into a pit and then hoist material out of the pit through the instrumentality of a counter-weight, the device being capable of use in pit silos, and for many other purposes. The device embodies a flexible element provided at one end with a receptacle and at the other end with a counter-weight, the flexible element being intermediately guided, and one object of the invention is to provide novel means to put a braking pressure on the flexible element at the will of an operator.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in elevation a device constructed in accordance with the invention, parts being broken away;

Figure 2 is a top plan;

Figure 3 is a transverse section showing the grip or braking lever in elevation;

Figure 4 is a perspective view of the fixed jaw.

In carrying out the invention, there is provided a support which may be in the form of a pair of parallel beams 1 extended across the top of a pit silo (not shown). The device comprises a guiding means, such as sheaves 2 and 3, spaced apart, the sheaves being located between the beams 1 and being supported at 4 for rotation on the beams.

The numeral 5 designates a block which is secured at 6 between the beams 1, the block being disposed between the sheaves 2 and 3. The block 5 is supplied at its ends with concavities 7, and between these concavities the block 5 is supplied in its upper edge with a

depressed seat 8. The block 5 may be alluded to as a fixed jaw, an appellation which will be understood better after the operation of the device has been described.

A flexible element 9 is looped over the sheaves 2 and 3 and slides along the concaved surfaces 7 of the block 5, the flexible element 9 having depending ends to one of which a receptacle 10 is secured, a counter-weight 11 being secured to the other end of the flexible element.

A means is provided whereby the receptacle 10 will be prevented from spinning around on a vertical axis, and this means includes a flexible line 14 connected at its ends to the receptacle 10 and to the counter-weight 11, the intermediate portion of the line passing slidably over a pulley 12 supported for rotation on one of the beams 1.

Figures 2 and 3 make it evident that a pair of upstanding fulcrum bars 15 are secured to one of the beams 1, a pair of upstanding guide bars 16 being secured to the other of the beams. The numeral 17 marks a grip lever disposed at right angles to the beams 1 and above the seat 8 in the block 5. The grip lever 17 is mounted to swing on a bolt 18 or the like that is carried by the fulcrum bars 15. The grip lever 17 can swing up and down between the guide bars 16. In its lower edge, the grip lever 17 has a notch 19 located above the intermediate part of the flexible element 9.

An actuating weight moves lengthwise of the grip lever 17. If desired, the grip lever 17 may be a trough, and the actuating weight 20 may be a disk or ball mounted to roll in the trough-shaped grip lever.

The rolling element 20 is held in the grip lever 17 by means of a retaining strip 21 that extends lengthwise of the lever, the ends of the strip 21 being secured to the ends of the lever. At a point between its ends, the strip 21 is attached to an inverted U-shaped bracket 22, the depending arms of which are connected to the sides of the lever 17. The means for tilting the lever 17 on its fulcrum 18 may comprise a pair of depending hand lines 23 connected to the lever at its ends.

The operator gets into the receptacle 10

and sinks slowly into the pit, the counter-weight 11 rising. A braking pressure can be put on the intermediate part of the flexible element 9, if desired, by tilting the lever 17 through the instrumentality of one of the hand lines 23. The weight 20 will roll to the left hand end of the trough or lever 17 in Figure 3, and cause the lever to bear on the flexible element 9: but when the weight 20 is at the right hand end of the part 17, as shown in solid line in Figure 3, then the weight acts to keep the lever 17 tilted clear of the line 9 so that the line can run freely.

After the operator gets to the bottom of the pit or far enough down into the pit so that he can load the ensilage, the lever 17 is tilted and the weight 20 rolls to the left in Figure 3 to cause the lever to grip the flexible element 9 and force it down into the seat 8 of the block or jaw 5. The receptacle 10 is loaded with the ensilage, and then the lever is tilted back into the position of Figure 3 where it will stay when the weight 20 rolls to the right hand end of the lever. The receptacle 10 with its load rises under the action of the counter-weight 11. When the receptacle 10 is at the top of the pit, the operator can tilt the lever 17 so that it will grip the flexible element 9 and hold the receptacle 10 whilst the ensilage is being shoveled or dumped out of the receptacle. The operator does not ride out of the pit, but climbs out after he has loaded the receptacle 10.

Referring to Figure 3 of the drawings, it will be noted that the fulcrum bolt 18 is not equally distanced from the ends of the lever 17. This is done so that one arm of the lever can be considerably longer than the other and make the weight 20 correspondingly effective as a means for swinging the longer part of the lever down and causing it to bind strongly on the intermediate part of the flexible element 9, much more force, of course, being required to hold the lever in braking position with respect to the flexible element 9 than is required simply to hold the lever out of engagement with the flexible element.

What is claimed is:—

1. In a device of the class described, a support, a guiding means on the support, a flexible element looped over the guiding means and having depending ends, a receptacle on one end of the flexible element, a counter-weight on the opposite end of the flexible element, a lever fulcrumed on the support and extended above the intermediate portion of the flexible element, an actuating weight movable along the lever, and means for tilting the lever, thereby to cause the flexible element to move longitudinally of the lever and to hold the lever in and out of engagement with the intermediate portion of the flexible element.

2. A device of the class described, constructed as set forth in claim 1, and further

characterized by the provision of a fixed jaw mounted on the support beneath the flexible element and the lever, the fixed jaw being provided with a depressed seat into which the lever presses the flexible element when the lever is tilted in one direction. 70

3. A device of the class described, constructed as set forth in claim 1, and further characterized by the fact that the lever is in the form of a trough, the actuating weight being mounted to roll in the trough. 75

In testimony that I claim the foregoing as my own, I have hereto affixed my signature.

FRANK ZWINK.
